DISPENSING MACHINE

Beno H. Baird, Dallas, Tex.

Application October 29, 1947, Serial No. 782,891

5 Claims. (Cl. 312—97.1)

1

This invention relates to new and useful improvements in dispensing machines.

One object of the invention is to provide an improved dispensing machine for vending bottled beverages or other articles, being of rugged, compact construction and having positive substantially fool-proof operating means.

Another object of the invention is to provide an improved dispensing machine having one or more rotatable reels or racks for receiving and storing a plurality of articles to be vended, there being means for controlling the rotation of each reel whereby the same moves intermittently or step by step to deliver or discharge the articles individually.

A particular object of the invention is to provide an improved dispensing machine, of the character described, wherein the reel is rotated by the gravity of the articles stored therein and the discharge of said articles from said reel is controlled by means associated therewith and arranged in such manner as to permit the delivery of only a single article upon each operation of the reel.

An important object of the invention is to provide an improved dispensing machine, of the character described, wherein the means for controlling the operation of the reel is rendered inoperative upon the discharge of the last article from said reel whereby the reel is positively locked against movement.

Another object of the invention is to provide an improved dispensing machine, of the character described, wherein the means for controlling the operation of the reel may be operatively disconnected therefrom to permit freewheeling of said reel and facilitate refilling thereof, there being means associated with the reel adapted to be swung to a closed position so as to prevent the discharge of articles from said reel during refilling of the same.

A further object of the invention is to provide an improved dispensing machine which includes a rotatable rack having individual compartments formed by longitudinal partitions having transverse projections for receiving articles therebetween, the partitions being disposed at the outer peripheral portion of the rack and terminating short of the hub thereof so as to lighten the weight of said rack and permit close spacing of the articles.

A construction designed to carry out the invention will be hereinafter described together with other features of the invention.

The invention will be more readily understood 55 ing and storing articles A to be vended which

2

from a reading of the following specification and by reference to the accompanying drawings, wherein examples of the invention are shown, and wherein:

5 Fig. 1 is an isometric view of a dispensing machine, constructed in accordance with the invention,

Fig. 2 is a side elevation view of the rotatable reel with bottles mounted therein,

10 Fig. 3 is a transverse, vertical, sectional view of a portion of the machine,

Fig. 4 is a horizontal, cross-sectional view of the machine, with the reel removed and showing the bottle retaining fence and its gates,

15 Fig. 5 is a transverse, vertical, sectional view, taken substantially on the line 5—5 of Fig. 4, with the reel in place,

Fig. 6 is a side elevational view of the machine, with the door and reel removed,

20 Fig. 7 is a perspective view of the reel operation control mechanism,

Fig. 8 is a detail view of the pawls of the control mechanism,

Fig. 9 is another perspective view of a portion 25 of the mechanism,

Fig. 10 is a sectional view of the ratchet wheel assembly of said mechanism,

Figs. 11, 12, and 13 are schematic views showing the relative positions of the pawls during operation of said control mechanism,

Fig. 14 is a detail view of the reel lock,

Fig. 15 is a side elevational view of a modified form of rotatable rack and retaining fence, and

35 Fig. 16 is a detail view of a modified ratchet and pawl assembly for controlling rotation of the reel or rack.

In the drawings, the numeral 10 designates a dispensing machine which includes an enclosed, upright housing or casing 11 of rectangular form and having suitably insulated walls 12. An access door 13 is provided in one side wall of the casing 11 and is adapted to be locked in the usual manner. Below the door 13, a horizontal partition 14 extends across the interior of the casing so as to provide an upper chamber 15 and a lower chamber 16 (Figs. 4 and 5). The upper chamber 15 functions as a cooling chamber and has cooling coils 17 therein extending to suitable refrigerating means (not shown) in the lower chamber 16. A support or frame 18 is mounted in the chamber 15 for rotatably supporting a reel or rack 19 between the coils 17. As will be herein- 40 after more fully explained, the reel 19 has a plurality of longitudinal compartments 20 for receiv-

50 ing and storing articles A to be vended which

have been illustrated as bottled beverages. For retaining the articles in the compartments 20 upon rotation of the reel, a substantially semi-circular fence or guard member 21 is supported by the frame 18 below and in close proximity or concentric relation to the lower peripheral portion or half of said reel. The fence 21 includes a pair of arcuate sections 22 and 23 having complementary curved gates 24 and 25 pivotally connected to their respective inner end portions. The gate 24 functions as a closure member and is normally swung downwardly to permit the discharge of articles from the reel to an inclined trough or chute 26 disposed therebelow, such discharge being controlled by the gate 25. A discharge opening 27 is formed in the front side wall of the casing for receiving the lower projecting end of the chute 26 which has its outer end closed by a retaining wall or stop 28. Rotation of the reel is controlled by an operating mechanism 29 having its actuating rod or handle 30 extending through the casing front wall. A cap remover and receptacle 31, of usual construction, may be mounted on the casing front wall.

The frame 18 is of skeleton construction and includes upright corner supports or legs 32 connected by suitable cross bars 33 extending horizontally between the ends and the intermediate portions of the legs and disposed at right angles to each other, whereby the interior of said frame is open and unobstructed. For rotatably supporting the rack or reel 19, a shaft 34 extends axially through said reel and has its projecting ends engaging in suitable brackets 35 carried by an opposed pair of the top cross bars 33. Thus, substantially one-half of the reel is positioned within the frame. The reel includes a pair of circular end plates 36 connected by an axial, cylindrical hub 37 which surrounds the shaft 34 (Fig. 3). A plurality of equally-spaced, longitudinal members or partitions 38 extend between and connect the peripheral portions of the end plates 36 and terminate considerably short of the hub 37. The partitions 38 are preferably triangular or wedge-shaped in cross-section, being radically disposed and having their apices directed inwardly (Fig. 5). A plurality of transverse ribs or projections 39 are formed on the tapered sides of the partitions in equally-spaced relation with the ribs of each partition being aligned with the complementary ribs of the other partitions to provide aligned divisions. It is noted that the compartments 20 are formed by the co-action of adjacent partitions and that said compartments are disposed in parallel relation, whereby the articles in the compartments are arranged in longitudinal and circumferential rows. The spacing of said partitions and ribs is in accordance with the size of the articles A, whereby said compartments are of sufficient area to accommodate said articles. As shown in Fig. 5, the inner ends of the articles engage the hub 36 which forms a bottom for each compartment. When the articles being vended are in the form of bottles, the reduced ends of the bottles are disposed in close proximity to one another and their enlarged bases are properly positioned by the wedge-shaped partitions. Manifestly, the diameter of the hub as well as the shape and spacing of the partitions and their ribs may be varied to conform to the character of the articles to be vended.

As set forth hereinbefore, the guard or fence 21 encircles the lower circumferential portion or half of the reel 19 to retain the articles in the

compartments 20. The arcuate fence sections 22 and 23 are preferably formed of a plurality of curved rods or bars 40 which are connected to and extend from immediately above the top cross bars 33 to a point adjacent one of the intermediate cross bars of the frame 18. Suitable transverse bars 41 connect the rods 40 to each other and angle brackets 42 secure the ends of the bars to the aforesaid intermediate cross bar of the frame (Fig. 4). One of the rods 40 is provided for each circumferential row of compartments and is preferably disposed intermediate the respective ribs of said compartments to support and prevent the articles from escaping therefrom. As shown in Fig. 5, the bases or outer ends of the articles engage and ride upon the rods. The complementary gates 24 and 25 form continuations of their respective fence sections and have arcuate fingers or rods 43 and 44 pivotally connected to the lower ends of the rods 40 of said fence sections (Fig. 4). A transverse bar 45, of less length than the fence bars 41, is welded or otherwise secured to the rods 44 of the gate 25, while the gate 24 has its rods connected by a pair of similar bars 46. When the gate 24 is swung upwardly, the free ends of its rods 43 are adapted to be disposed in substantially abutting relation to the adjacent ends of the gate rods 44 so as to prevent articles from being discharged into the chute 26. In order to control the discharge of the articles and provide a single delivery upon each operation of the reel, the rods 44 are of progressively increasing length and the complementary rods 43 are of progressively decreasing length from the front to the back of the gates. Due to the stepped relation of the rods 44, one division of one of the reel compartments is moved beyond the end of its respective rod upon each actuation of the reel to discharge a single article. Thus, articles in adjacent divisions of the same compartment are discharged individually upon the intermittent operation of the reel until said compartment is emptied. At this point, the first division of the adjacent clockwise compartment is in such position that the article therein is discharged upon the next operation of the reel.

Downward movement of the gate 25, which functions as a discharge control member, is limited by the engagement of its rods 44 with the upper surface of the chute 26. The latter is inclined upwardly from the discharge opening 27 and extends at angle to the axis of the reel 19 so as to underlie the opening formed by the gates. Although of any suitable construction, the chute is substantially semicircular in cross-section and has its upper end suspended from the frame 19. A depending plate 47, having a circular opening 48, supports the discharge end of the chute. Swinging of the gate or closure member 24 is controlled by a lever 49 which is pivotally connected to a link or bar 50 carried by the forward end of said gate. The lever 49 extends transversely beneath the reel and above the discharge end of the chute and terminates adjacent the door 13, as shown in Figs. 3, 4 and 5. A notch 49' is formed in the outer end of the lever for engaging an angle bracket 51 secured to one of the frame legs 52 to fasten the closure member in its lowered or open position (Fig. 9). Upon opening the door 13 and moving the lever outwardly, the closure member is swung upwardly to its closed position. The lever carries a curved deflector plate 52 which extends parallel to and adjacent the lower end of the chute for direct-

ing articles discharged from the reel into said chute.

The rack or reel 19 is adapted to be rotated by gravity or the weight of the articles stored therein and the compartments 20 and partitions 38 are omitted from one portion 53 of said reel (Figs. 2 and 5) to insure such rotation. Since the reel rotates in a counter-clockwise direction (Fig. 5), the void portion 53 is positioned counter-clockwise or to the right of the gate or control member 25 prior to placing the machine 10 in operation after each refilling of said reel. The reel is counterbalanced by suitable weights (not shown) so that the same may be readily turned about its axis when empty. As has been explained, rotation of the reel is controlled by the operating mechanism 29 which includes a ratchet wheel assembly 54 mounted upon the frame 18 adjacent the gate 25. A toothed disk or circular plate 55 is carried by one of the end plates 36 for coacting with the ratchet wheel assembly 54 and the peripheral radial teeth 56 thereof are preferably rounded or curved.

As is most clearly shown in Figs. 9 and 10, the ratchet wheel assembly includes an axial shaft 57 extending parallel to the reel shaft 34 and having one end journaled in an opening 58 formed in an upright brace 59 of the frame. The opposite end of the shaft 57 is slidably mounted in a bearing 60 which is supported by a bar 61 extending transversely of the frame and secured to the cross bars 33 thereof. A small spool 62 is carried by the shaft between the frame brace 59 and bearing 60 and has a plurality of equally-spaced, longitudinal rods or pins 63 at its peripheral portion for engaging the teeth 56 of the reel disk 55. The spacing of the teeth and pins is such that a slight rotation of the reel is permitted upon each engagement of one of said rods with one of said teeth and this rotation is sufficient to move one of the articles A past its respective finger 44 of the gate 25. A ratchet wheel or disk 64, having angular, clockwise-directed teeth 65, is mounted on the shaft 57 at one end of the spool and is adapted to coact with a pair of pivotally-mounted pawls 66 and 67 (Figs. 7 and 8) for controlling the rotation of said spool and the reel. The ratchet wheel 64 is maintained in coacting relation to the pawls 66 and 67 by a leaf spring 68 secured to the frame brace 59 in overlying relation to the end of the spool shaft which projects through the opening 58.

For moving the ratchet wheel out of engagement with the pawls to permit free-wheeling of the reel when it is desired to refill the same, a bell-crank 69 is pivotally mounted upon the bar 61 and has an upstanding pin 70 engaging the end of the spool shaft which is slidably mounted in the bearing 60. A lever 71 has one end connected to the free end of the bellcrank 69 and its opposite end to a link 72 which is pivotally supported by the bar 61. The link 72 depends below the bar and has a transverse pin 73 adapted to be engaged by a lug or projection 74 carried by the gate lever 49. Upon outward movement of the gate lever, its lug 74 strikes the pin 73 so as to swing the link 72 in a clockwise direction and move the lever 71 longitudinally to the right, thereby pivoting the bell-crank 69 in counter-clockwise direction. Due to the engagement of the pin 70 with the shaft end, said shaft is slid longitudinally to the left so as to move the ratchet wheel out of coacting relation with the pawls. The spool pins 63 are of sufficient length to permit this longitudinal movement and remain in

engagement with the teeth 56 of the reel disk, whereby the spool and ratchet wheel as well as the shaft rotate with the reel upon free wheeling thereof. Since the spring 68 is constantly urging the ratchet wheel into engagement with the pawls, the above elements are returned to their position shown in Fig. 9 upon disengagement of the lug 74 with the link pin 73.

As is most clearly shown in Figs. 7 and 8, the pawls 66 and 67 are carried by closely spaced collars or tubular posts 75 and 76 which are rotatably mounted upon an inclined support or base 77 secured to one of the frame cross bars 33. A pair of links 78 and 79 are connected to the posts 75 and 76 and are pivotally connected to each other by a cross arm 80, whereby reciprocal movement of the links causes oscillation of both of said posts and their pawls. The latter are in the form of flat arms or blades 81 which project toward each other in overlapping, vertically-spaced relation, being disposed between the posts and oscillating in opposite directions upon turning of said posts. As shown by the numeral 82, the leading edges of the blades 81 are bevelled for coacting with the inclined surfaces of the ratchet teeth 65. The relative positions of the pawls and ratchet teeth are best illustrated in Figs. 11, 12 and 13. In Figs. 8 and 11, the pawls are shown in their normal positions prior to actuation of the control mechanism 29. In Figs. 7 and 12, the pawls are shown in an intermediate or half-way position with the upper pawl 76 being retracted out of engagement with one tooth and the lower pawl 77 engaging the adjacent counter-clockwise tooth prior to engagement of said upper pawl with said latter tooth. The links 78 and 79 have been reciprocated to the left so as to turn the posts 75 and 76 in a counter-clockwise direction, while the spool 62 and its pins 63 have revolved in a similar direction to permit rotation of the reel 19 in an opposite direction. Reverse reciprocation of the links causes reverse oscillation of the posts and their pawls, whereby the pawl 77 moves out of engagement with the adjacent tooth and the pawl 76 moves into engagement therewith. As shown in Fig. 13, the upper pawl moves into the path of the tooth prior to the disengagement of the lower pawl therefrom. After full reciprocation of the links and oscillation of the pawls, the ratchet wheel and spool revolve the distance between adjacent ratchet teeth to permit a similar rotation of the reel. This amount of movement is sufficient to move one of the articles A past its respective gate finger 44 and permit the discharge of said article into the chute 26. Due to the bevelled edges 82 of the pawl blades 81, said blades ride along the inclined surfaces of the ratchet teeth and force rotation of the ratchet wheel in the event the same sticks due to freezing.

The link 78 is elongated and is connected to one end of a traverse lever 83 which has its opposite end fastened to one leg of a pivoted hanger 84 which depends from one of the frame cross bars 33 (Fig. 7). An elongated link or bar 85 connects the other leg of the hanger 84 to the operating plunger 30, whereby reciprocation of said plunger is transmitted to the link 78 by swinging of the hanger and the lever 83. If desired, a plurality of openings 86 may be formed in each hanger leg to permit adjustment of the connections between the above elements. In order to lock the control mechanism and render the same inoperative, a small plate or flange 87 projects laterally from the bar 85 in close prox-

imity to an angular arm 88 carried by the gate 25. The arm 88 is counterbalanced by a suitable weight 89 so as to swing downwardly into the path of the flange 87 to prevent movement of the bar 85 when no article is resting upon the fingers 44 of the gate. However, this weight is insufficient to lift the gate when an article is resting thereupon. Upward swinging of the gate is limited by an angle bracket 90 mounted on the frame and overlying a cross bar 91 projecting laterally from said gate (Fig. 4). For locking the reel 19 against rotation, a lock bolt or plunger 92 is slidably mounted upon the uppermost frame cross bar 33 adjacent the door 13 in a suitable housing 93 and extends at a right angle to the reel disk 55 for engaging the notched periphery thereof. The housing 93 has an angular or L-shaped slot 94 for receiving a handle 95 carried by the plunger 92 and preventing engagement of said plunger with the disk teeth 66 except when the door is open (Fig. 14).

In placing the herein described machine in operation, the door 13 is opened and the lever 49 pulled outwardly so as to swing the gate or closure member 24 upwardly and dispose its fingers 43 into underlying relation to the circumferential rows of the reel compartments 20. At the same time, the lug 74 of the lever strikes the pin 73 of the link 72 to reciprocate the lever 71 and swing the bell-crank 69 with its pin 70 so as to slide the spool shaft 57 longitudinally for disengaging its ratchet wheel 64 from the pawls 66 and 67. The reel 19 may now be readily rotated by hand and its compartments filled with bottles or other articles to be vended. During the filling step, the lock plunger 92 may be engaged with the notched periphery of the reel disk 55 whenever desired to prevent rotation of the reel. As soon as articles rest upon the fingers 44 of the gate 25, (Fig. 5), the arm 88 is swung upwardly out of the path of the flange 87 of the bar 85 to unlock the control mechanism 29 (Fig. 7).

When the filling of the reel is completed, the same is rotated so as to dispose its void 53 above the gate 24 with the adjacent clockwise compartment 20 above the ends of the fingers 44 of the gate 25 as shown in Fig. 5. The lever 49 is then pushed inwardly to swing the gate 24 downwardly to its open position and move the lug 74 out of engagement with the link pin 73, whereby the spring 68 slides the spool shaft longitudinally so as to dispose the ratchet wheel in coacting relation to the pawls 66 and 67. During re-engagement of the ratchet wheel with the pawls, the lock plunger 92 is engaged with the teeth 65 of the disk reel to maintain said reel in position. The machine is now ready for operation. Although not illustrated in detail, actuation of the operating plunger 30 is controlled by a coin device C of the usual construction. As has been described, inward movement of the plunger is transmitted by the bar 85, hanger 84 and lever 83 to the link 78 and from said link to the link 79 by the cross arm 80 so as to oscillate the posts 15 and 16 and their pawls 66 and 67 from the position shown in Figs. 8 and 11 to the position shown in Figs. 7 and 12. Due to the disengagement of the upper pawl and engagement of the lower pawl, limited counter-clockwise rotation of the ratchet wheel 64 and the spool 62 and clockwise rotation of the reel 19 are permitted. Outward movement of the plunger swings the pawls to the position shown in Fig. 13 and then returns the same to their original position (Fig. 11). The ratchet wheel, spool and

reel rotate the distance between adjacent ratchet teeth and this distance is sufficient to move the first article in the first clockwise compartment past the gate finger 44 therebelow, whereby said article drops into the chute 26 and slides through the discharge opening 27. Upon the next operation of the plunger 30, the next article in the second or adjacent division of the same or first clockwise compartment is discharged in the same manner as are the remainder of the articles upon subsequent operations. When the reel is emptied, no bottles rest upon the gate 25 and the weight 89 swings the arm 88 downwardly into the path of the bar flange 87 to lock the control mechanism against operation.

As shown in Fig. 15, the compartments of the reel or rack may extend in longitudinal rows at an angle and the rods or fingers of the gates may be of equal lengths. A rack 96 of this construction is similar to the reel 19 and has compartments 97 formed by longitudinal partitions 98 which extend at an angle to the axis of said rack. For retaining the articles A in the compartments 97, a modified form of gate or discharge control member 99 is provided and has curved rods or fingers 100 of equal length underlying the circumferential rows of said compartments. The rods or fingers 101 of the other gate or closure member 102 are also of equal length to coact with the fingers 100. The operation of this rack and these gates is the same as described hereinbefore.

Instead of the ratchet wheel assembly 54, the pawls of the control mechanism may coact directly with the reel 19. As shown in Fig. 16, an annular ratchet 103 is secured to the periphery of one of the end plates 36 in place of the notched or toothed disk 55. The ratchet 103 has angular, clockwise directed teeth 104 which are adapted to be engaged by a pair of overlapping pawls 105 and 106, substantially identical to the pawls 66 and 67 and being reversed or turned over due to their direct relation to the reel. These ratchet teeth and pawls coact in the manner described to control the rotation of the reel.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. An article dispensing machine including, a casing, a reel rotatably supported in the casing, the reel having a plurality of longitudinally elongate radial compartments adapted to receive radially positioned articles, retaining means circumferentially surrounding the lower peripheral portion of the reel for confining the articles in the compartments, the retaining means having a transverse opening therein extending longitudinally of the reel for registration with the compartments, the opening and compartments being misaligned relative to each other whereby the articles individually and successively register with said opening and fall therethrough upon rotation of said reel, an inclined discharge chute communicating with said opening and projecting exteriorly of said casing, a mechanism for controlling rotation of the reel, the mechanism including a ratchet wheel, and a pair of separate oscillating pawls for engaging and coacting with the ratchet wheel, the pawls being disposed transversely relative to the teeth of said wheel so as

to force rotation of the latter in the event the latter sticks due to freezing.

2. In a dispensing machine, a rotatable article receiving rack including, an axial hub, partitions extending radially of the rack and coacting with the hub to provide longitudinally elongate radial compartments for receiving radially positioned articles, a retainer adjacent the lower portion of said rack for normally retaining articles in the compartments, the retainer having a discharge opening extending longitudinally of said rack with which portions of said compartments successively register, the opening and compartments being angularly disposed relative to each other whereby the articles individually register with and are discharged through said opening, a mechanism for controlling rotation of the rack, a pivoted member forming a part of said retainer and disposed adjacent its opening for supporting and controlling the passage of articles therethrough, and means projecting from the member to a point contiguous to the path of movement of a portion of the control mechanism, said member being depressed by the weight of the articles resting thereupon so as to pivot upwardly when void of articles and dispose its projecting means in the path of said mechanism portion for locking the same against operation.

3. In a dispensing machine, a rotatable rack having a plurality of compartments therein, each compartment receiving a plurality of radially positioned articles, a retainer adjacent the lower peripheral portion of the rack for retaining the articles in the compartments and having a discharge opening, the opening and the compartments being misaligned whereby a single article is successively registered with said opening, a mechanism for controlling rotation of the rack which includes a ratchet wheel rotatable with said rack, a pair of coacting pivoted pawls adapted to be oscillated simultaneously in opposite directions for engaging and disengaging said wheel to permit limited rotation of said rack, operating means connected to the pawls for oscillating the same, a closure for said opening, and means rendering

45

the control mechanism inoperative upon closing of the closure.

4. In a dispensing machine, a rotatable rack having a plurality of compartments therein, each compartment receiving a plurality of radially positioned articles, a retainer adjacent the lower peripheral portion of the rack for retaining the articles in the compartments and having a discharge opening, the opening and the compartments being misaligned whereby a single article is successively registered with said opening, a mechanism for controlling rotation of the rack which includes a ratchet wheel rotatable with said rack, a pair of coacting pivoted pawls adapted to be oscillated into and out of engagement with the ratchet wheel, and operating means connecting the pawls for oscillating the same simultaneously in opposite directions whereby one pawl is engaged while the other pawl is disengaged to permit limited rotation of said rack and re-engagement of the latter pawls, the ratchet wheel being movable out of engagement with said pawls to permit rotation of said wheel and the rack relative to said pawls for refilling said rack.

5. The combination set forth in claim 4 including, a closure for the discharge opening of the retainer, a lever for moving the closure into a closed position, and means actuated by the lever for moving the ratchet wheel out of engagement with the pawls.

BENO H. BAIRD.
